GATE.

No. 19,771.

Patented Apr. 22, 1890.

UNITED STATES PATENT OFFICE.

JOHN McLEAN, OF BROOKLYN, NEW YORK.

DESIGN FOR A GATE.

SPECIFICATION forming part of Design No. 19,771, dated April 22, 1890.

Application filed March 21, 1890. Serial No. 344,831. Term of patent 7 years.

To all whom it may concern:

Be it known that I, JOHN McLEAN, a citizen of the United States, residing at Brooklyn, in the county of Kings and State of New York, 5 have invented and produced a new and original Design for a Gate, of which the following is a specification, reference being had to the accompanying drawing, forming part thereof, which shows a face view of my new design for 10 a gate.

This invention relates to a new shape and ornamentation of a gate, the main feature of the design being the ornamental scrolls *a*

near the center of the gate, the ornamental rosettes *b* near the ends thereof, the ornamental scrolls *c* above and below said rosettes, and the ornamental top pieces *e* at the top of the gate, all as shown in the drawing.

Having now described my improved design, what I claim is—

The design for a gate having the shape and ornamentation herein shown and described.

JOHN McLEAN.
